UNITED STATES PATENT OFFICE

141,319

DESIGN FOR A DISPLAY RACK

Warren Wheary, Evanston, Ill.

Application September 29, 1944, Serial No. 115,516

Term of patent 7 years

(Cl. D80—9)

To all whom it may concern:

Be it known that I, Warren Wheary, a citizen of the United States, residing in Evanston, in the county of Cook, State of Illinois, have invented a new, original, and ornamental Design for a Display Rack, of which the following is a specification, reference being had to the accompanying drawing, forming part thereof.

The single figure of the said drawing constitutes a perspective view of the display rack embodying my design.

I claim:

The ornamental design for a display rack, substantially as shown.

WARREN WHEARY.
